(Cl. D58—13)

To all whom it may concern:

Be it known that I, Giuseppe Tavolazzi, a citizen of Italy, residing at Missaglia, Como, Italy, have invented a new, original, and ornamental Design for a Double Toolbox, of which the following is a specification, reference being had to the accompanying drawing, forming a part hereof.

In the drawing:

Figure 1 is a top perspective view of a double toolbox, showing my new design;

Fig. 2 is a top perspective view of the toolbox shown in Fig. 1, the covers being removed; and

Fig. 3 is a bottom perspective view of the toolbox shown in Fig. 1, the covers being removed.

The sides of the box not shown are the same as those shown.

I claim:

The ornamental design for a double toolbox, as shown and described.

GIUSEPPE TAVOLAZZI.
